UNITED STATES PATENT OFFICE.

WALTER LARKIN, OF NORRISTOWN, PENNSYLVANIA, ASSIGNOR TO FIDELITY MACHINE COMPANY, OF PHILADELPHIA, PENNSYLVANIA, A CORPORATION OF DELAWARE.

STRIPING ATTACHMENT FOR KNITTING MACHINES.

Application filed July 19, 1923. Serial No. 652,541.

One object of my invention is to provide an attachment for circular knitting machines for automatically delivering thereto a continuous length of the yarn or thread of different colors or materials, and said invention more particularly comprises mechanism whereby predetermined lengths of yarn shall be automatically tied, knotted or otherwise connected together and delivered to the knitting mechanism while this is in operation.

Another object of my invention is to provide a striping attachment for knitting machines which may be mounted at a convenient point at a distance from and independently of the needle cylinder, so that free access may be had to the latter and in order that there may be sufficient room to permit of any of a number of different yarns being successively fed to the machine;—the invention contemplating a yarn changing mechanism particularly adapted for use with, though not limited to a machine employing bobbins, needle cylinder and dial all of which are stationary.

I further desire to provide a practical, relatively simple pattern-controlled mechanism for automatically connecting together and successively delivering to a knitting machine, any two of a number of different yarns while said machine is in operation and without interfering with the knitting thereby of a fabric; the invention including novel means for grasping and holding all of a number of yarn ends while another yarn is being fed to the machine.

I also desire to provide a simple and reliable means for automatically selecting any one of a number of different yarns, connecting it to another yarn which is being delivered to the needles of a knitting machine, and after cutting off said latter yarn, delivering the selected yarn to said machine.

Another object of my invention is to provide novel means for automatically controlling the operation of a knotting and cutting off mechanism in order to substitute one of any of a number of different yarns in any desired lengths, after a predetermined length of another yarn has been delivered to a knitting machine.

A further object of the invention is to

provide an attachment having the above characteristics, which may be easily and quickly applied to a circular knitting machine without requiring material alteration thereof, in order to enable said machine to produce goods of different patterns, colors or materials.

It is also desired to provide a simple and reliable attachment for automatically selecting and delivering to a knotting device any two of a number of yarns or threads for the purpose of causing these to be tied together, and the invention also includes the combination of such an attachment with a takeup device so arranged as to permit of the necessary interruption in the feed of the yarn without interfering with the continuous operation of the knitting machine with which the attachment is used.

I also desire to provide a novel combination of yarn connecting device with the stop motion mechanism of a knitting machine so that the latter will be stopped in case said connecting device fails to function properly.

These objects and other advantageous ends I attain as hereinafter set forth, reference being had to the accompanying drawings in which,

Fig. 1 is a front elevation showing my invention as applied to a circular knitting machine;

Fig. 2 is a side elevation of the apparatus shown in Fig. 1;

Fig. 3 is a front elevation on a larger scale than Figs. 1 and 2, illustrating in their normal positions the main parts of the attachment constituting my invention;

Fig. 4 is a side elevation of the mechanism shown in Fig. 3, a portion of the frame being shown in section;

Fig. 5 is a front elevation similar to Fig. 3, showing the parts in the positions occupied after the operation of the selecting mechanism and during the operation of the knotting mechanism;

Fig. 6 is an end elevation similar to Fig. 4, but showing the parts in the positions illustrated in Fig. 5;

Fig. 7 is a plan partly in section and on a scale larger than that of Figs. 3 to 6 inclusive, illustrating the knotting device and certain of its associated mechanism;

Fig. 8 is a front elevation of the parts shown in Fig. 7;

Fig. 9 is a perspective view of the yarn holding device, shield and guard plate with certain of their associated parts;

Fig. 10 is a detached perspective view of the yarn end holding and guiding mechanism;

Fig. 11 is a perspective view, partly in section, of the selector mechanism and certain of the parts associated therewith;

Figs. 12, 14, 16, 18, 20 and 22 are front elevations, to some extent diagrammatic, illustrating the operation of my invention;

Figs. 13, 17, 19, 21 and 23 are side elevations showing the parts in positions respectively illustrated by Figs. 12, 14, 16, 18, 20, and 22;

Fig. 15 is a side elevation of the parts shown in Fig. 14;

Fig. 19^a is a diagram illustrating the relative positions of the two active threads being operated on by the parts shown in Figs. 18 and 19;

Figs. 24 to 32 inclusive are perspective views illustrating the operation of the knotting mechanism and its associated parts;

Figs. 27^a, 28^a, 29^a, 30^a, and 31^a, are perspective views illustrating certain of the steps of forming the knot;

Fig. 33 is an elevation illustrating diagrammatically a body of striped fabric which my attachment is designed to produce;

Figs. 34 and 35 are a front and a side elevation respectively illustrating the action of part of my invention;

Fig. 36 is a side elevation partly in vertical section showing the detail construction of the selector and certain of its associated parts;

Figs. 37 and 38 are a front and a side elevation respectively illustrating the construction and mounting of the preferred form of carrier arm and its associated parts;

Fig. 39 is a plan of the mechanism shown in Figs. 37 and 38; and,

Figs. 40 and 41 are perspective views showing the detail construction of two of the elements employed in the preferred form of my invention.

In Figs. 1 and 2 of the above drawings, 1 represents a portion of the frame of a well known form of circular knitting machine, which in the case illustrated, is of the dogless dial type, described and claimed in my U. S. Patent No. 1,433,884, dated October 24, 1922. The upper part of said frame 1 carries a circular bed plate 2 providing a bearing for a rotary cam ring 3 and supports a stationary needle cylinder 4. Said bed plate also carries posts 5 supporting a yoke 6 which serves to carry and hold from rotation a dial post 7, on whose lower end is mounted the dial of the knitting machine.

The cylinder cam ring 3 likewise carries a pair of posts 8 supporting a yoke 9 which serves to support and drive a dial cam ring 10.

The cam ring 3 is driven through gearing (not shown) mounted within a closed casing 11 and driving a horizontal shaft 12 journaled in bearings in the frame 1. This shaft has fixed to its free end a cylindrical enlargement 13 whose outer face has a crank pin 14 on which is mounted a pawl 15, for engaging and intermittently turning a pattern wheel which governs the operation of the knitting machine. The frame 1 has fastened to it a bracket providing a bearing 17 for a countershaft 18, which has fixed to its outer end a sprocket wheel 19, in the present instance having its teeth formed with two series of radial notches 20 for the reception of the two runs of a pattern chain 21 whereby the operation of my invention is controlled. The shaft 18 also carries a ratchet wheel 22 engaged by a hooked pawl 23 forming part of or attached to the strap 24 of an eccentric 25 on the driven shaft 12. The rotation of this shaft through the pawl 23 and ratchet wheel 22, intermittently turns the sprocket wheel 19 and the pattern chain 21 thereon.

That portion of the frame 1 on which the pattern wheel 16 is mounted, has pivoted to it a selector lever 26 which includes an arm carrying a roller 27 (Fig. 2) positioned to be engaged by certain high links of the pattern chain 21. Said chain includes in the present case four sets of these links indicated at 21^a, 21^b, 21^c, and 21^d, of varying heights or degrees of projection, so that as they are brought under the roller 27 by the rotation of the sprocket wheel 19, the lever 26 is turned on its pivot or fulcrum 28 through corresponding angles. The free ends of this lever 26, through a link 29, is connected to one arm of a bell crank lever 30 acted on by a spring 31 to at all times draw said lever 26 and hence its roller 27, toward the pattern chain 21.

As shown in Figs. 1 and 2, the machine has a bracket or plate 32 projecting horizontally for the support of a vertically extending post 33 on which is mounted a casing 34 containing part of the stop motion mechanism. Said bracket also carries a vertically extending rod 35 projecting considerably above the top of the machine and carrying at its upper end a second casing 36 in which is pivoted one end of a projecting yarn guiding finger 37. This latter also forms part of the stop mechanism of the machine and actuates said mechanism when drawn downwardly beyond a predetermined point. The mechanism in the casing 34 is controlled by a movable arm having a series of parallel fingers 39 positioned to coact with a stationary grid 40, the arrangement being such

that fingers and grid are maintained substantially parallel and immediately adjacent each other under operating conditions by the length of yarn passing between them 5 and running through the eye carried by the finger 37 down to the knitting mechanism. In the event of breakage of the yarn the arm with the fingers 39 is released and its fall from the position shown causes operation 10 of the stop motion.

In accordance with my invention, I utilize the lower portions of the posts or rods 33 and 35 to support a frame 41 which may be held thereto in any desired or suitable 15 manner and to which is fulcrumed the bell crank lever 30. For this purpose, I rotatably mount in said frame a spindle 42 on which said lever is journaled. This spindle within the frame also has mounted upon it 20 a beveled gear 43 whose teeth mesh with those of a beveled pinion 45 formed integral with a sleeve 45^a rotatably mounted on a fixed spindle 46, (Fig. 11) whose inner end is fixed in any suitable manner to and carried by the frame 41. The outer end of the sleeve 45^a has formed integral with it a radially projecting arm 47 serving to support a yarn carrier which in the case illustrated in Figs. 1 to 35 has the form of a 25 ring or wheel 44 concentric with the sleeve 45^a and fixed spindle 46. However, I preferably give it the form shown in Figs. 37 and 38 at 44^c so that it has an angular outline with a relatively wide advancing end. 30 As shown in Fig. 8, for example, this carrier ring is peripherically grooved like a grooved pulley for about one-half of its circumference and when the device is in its normal position (Fig. 3) this grooved portion 35 of the ring lies for the most part on the left side of its vertical diameter. As shown in Fig. 4, the lower or advancing end of the grooved rim has an angular recess 44^a so as to facilitate its engagement with 40 and movement of the various lengths of yarn and their guidance into the groove 45^a of said ring.

To the rear of and parallel with the shaft 42, the frame 41 carries a fixed rod 48 (Figs. 50 5 and 36) on which are pivoted any desired number, in the present instance four, 55 yarn guide fingers 49, 50, 51 and 52. Each of these consists of an elongated bar extending downwardly and forwardly from the rod 48 and having its lower end curved 60 forwardly and upwardly, each bar being perforated adjacent its extremity for the reception of one of a number of yarns to be delivered to the knitting machine. These 65 yarn guide fingers are at all times pressed upwardly toward a normal position in which they engage a cross bar 53 (Figs. 4 and 5) by springs 54 preferably coiled on a rod 55 supported at the rear of the frame 41. 70 Any one of said fingers may be depressed

from its normal elevated position to a lowered position (Fig. 6) by a selector 56 which is rotatably as well as longitudinally movable on the spindle 42 and which has a width slightly less than that of any one of 75 the various fingers.

For rotating this selector, the beveled gear 43 has fixed in and projecting laterally from it a pin 57 which extends through a suitable opening in said selector so that the latter 80 is necessarily rotated with said gear regardless of its distance from the same or of its position upon the shaft 42. Said selector has a projecting hub 58 formed with an annular recess for the reception of an 85 arm 59, fixed on a selector rod 60 slidably guided in portions of the frame 41 (Figs. 3 and 11). One end of this rod has a projecting pin 61 operative in a slot 62 formed in the selector cam 63 which is fixed to and 90 moves with the bell crank lever 30.

With this arrangement of parts, the swinging of said lever 30 on the shaft 42 moves the selector cam 63 concentrically with said shaft and causes the wall of the 95 cam slot 62 to co-operate with the pin 61 to move the selector rod 60 longitudinally to an extent dependent upon the arc of movement of said bell crank lever. The parts are so arranged that when the pin 61 is in its 100 normal position at the lower end of the cam groove 62, the selector rod 60 with the arm 59 holds the selector 56 in a vertical plane including the extreme right hand yarn guiding finger 49. If now the gear 43 be 105 turned, the consequent rotation of said selector by the pin 57 will cause this particular yarn guiding finger to be depressed. Obviously, by varying the arc of movement of the bell crank lever 30, the selector cam 110 63 may be caused to act on the selector 56 to position it in the plane of any one of the other yarn guides 50, 51 and 52. As previously noted the bell crank lever 30 is actuated through the lever 26 and the bar 115 29 from the different high links of the pattern chain 21.

Immediately above the sleeve 45^a of the beveled pinion 45, I mount a knotting and cutting off device 64 which may be of any 120 suitable construction. Since however the detail mechanism of this device constitutes no part of my invention, it has not been illustrated. Said device includes three co-acting knotting, clamping and cutting blades 125 65, 65^a and 66 of angular form pivotally connected and lying immediately adjacent each other. These blades are actuated by a spindle 67 which extends vertically through the knotter and has fixed to it an operating arm 68 normally maintained in and drawn toward a definite position by means of a coil or other suitable spring 69. For oscillating the arm 68 to operate the knotting 130 and cutting blades, I provide a pin 70 pro-

jecting from said arm and engaged by one end of an arm 71 (Figs. 4 and 7) whose opposite end is fixed to a vertical spindle 72 journaled in suitable bearings in the frame 41. This vertical spindle has fixed to its lower portion a second arm 73^a carrying a replaceable shoe 73 which projects toward the cylinder cam ring 3.

For the purpose of periodically actuating this arm 73 and hence the tying and cutting blades, I mount on the cylinder cam ring 4 or other rotary part of the machine in timed relation with said ring, a cam 74 (Figs. 2 and 4) and while this cam would ordinarily engage the arm 73 at each revolution of the cylinder, I prevent such engagement except when desired by making the spindle 72 vertically slidable in its bearings so that said arm is normally held at a level above that of said cam 74. For this purpose, I fix to said spindle 72 a third arm 75 which rests on the selector 56 and make the under face of said arm substantially horizontal or parallel with the pin 57, so that it engages with the selector regardless of its position relatively to the yarn guiding fingers 49 etc. Normally said selector holds the arm 75 and with it the second arm 73 raised so that the latter cannot be engaged by the cam 74 on the cylinder cam ring. When however the selector 56 is rotated to depress one of the yarn guiding fingers 49—52, said arm 73 is likewise lowered and it may be engaged by the cam 74 so that the spindle 72 will be turned to operate the knotting device at the next rotation of the said cylinder cam ring.

For actuating the beveled gear 43 and its associated parts at such times only as their action is desired, I fix to the driving shaft 12 an eccentric 76 having mounted thereon a strap connected through a rod 77 with a lever arm 78 on a spindle 79 carried by the bracket 32. Said lever includes an arm 77^a and a tooth 80, designed to be engaged by a spring actuated pawl 81 pivoted to a second lever 82 on the spindle 79, so as to transmit motion from said first lever 78 to said second lever. The latter includes also an arm in which a set screw 82^a is adjustably mounted in position to be engaged by the arm 77^a to positively move the lever 82 in a direction opposite to that in which it is moved through the pawl 81. A controller cam 83 connected to a third lever 84, also rotatably carried by the spindle 79, normally holds the pawl 81 in such a raised position that the oscillation of the lever 78 by the rod 77 cannot affect it or the lever 82. This third lever through a link 85, is connected to the bell crank lever 30, and the arrangement is such that when the latter is turned from its normal position by any one of the high links of the pattern chain 21, the controller cam 83 is thereby turned into a posi-

tion to permit the pawl 81 moving into engagement with the tooth 80, thus causing the arm 82 to be moved at the next forward movement of the lever arm. The arm 82 through a link 86, is connected to a pin 87⁷⁰ on the beveled gear 43 so that the latter may be turned by said arm through such an arc as will cause turning of the pinion 45 and of the ring 44 through an angle of somewhat more than 180°.

For holding the ends of any three of the yarns *w*, *x*, *y*, and *z* while the fourth is being drawn into the knitting machine, I provide the elements shown in detail in Figs. 9 and 10, and these include a flat segmental shield 88 mounted on a block 89 held by a screw 90 to the fixed stud 46 on which is carried the sleeve 45^a. The curved periphery of this shield is concentric with the carrier ring 44 and on the left side of its center it has fixed to its front face a second block 91 on the front of which a pair of superposed angular guide plates 92 and 93 are held by suitable means such as the screws 94 (Fig. 12). The inner one of these two plates has a downwardly curved guide lip 95 at whose inner end is a yarn receiving recess 96 and its top otherwise flat face is grooved or serrated to facilitate holding the yarn or thread thereto.

The outer guide plate 92 has a second yarn guiding lip 97 extending horizontally over and substantially parallel with the lip 95 and the inner edge of said plate is toothed or notched as indicated at 98 to assist in holding the several yarn ends from movement as hereinafter described. In addition I provide this plate with a notch or recess 98^a for holding and guiding a thread at certain times during operation of my invention.

Above and spaced away from the top of the lip 97 is a forked or notched guide plate 99 projecting upwardly at an acute angle to the horizontal and held in position by a screw 100 (Figs. 10 and 12). The notch of this third guide plate and the recesses 96 and 98^a of the two members 93 and 92 are arranged one above the other and all above the top and inner edge of a guard plate 101 held in place by the screws 94 and projecting in front of the lower right hand portion of the shield 88. As shown in Fig. 9, the outer lower edge of this shield plate is bent inwardly to form a guard lip 102, spaced away from and outside of the curved edge of the shield 88, which is mounted to lie substantially in the plane of the groove of the carrier ring 44.

Immediately above the flat face of the block 91 and under the horizontal top of the angle plate 93 is a temporary yarn holder 103 in the form of a flat plate pivotally mounted on a screw 104 set in the block 91 (Fig. 12) and having its free end distant

from said screw inclined as shown in Fig. 10. A spring 105 mounted on said screw 104 is operative on this holder to force its inclined end toward the adjacent flat face 5 of the shield 88, so that one or more ends of yarn extending vertically between the shield and guard plate and upwardly through the recesses 96 and 98^a at the inner ends of the guide lips 95 and 97, will be gripped and 10 temporarily held from dropping down.

For frictionally holding the ends of the yarns not being fed, I connect to the lower end of the spindle 67 of the knotter 64 a laterally projecting hooked arm 106 (Fig.

15) 10) having one edge serrated and designed to operate between the horizontal portions of the angle plates 93 and 92 and to frictionally coat with the roughened top face of the former to tightly grip and normally 20 hold from movement the yarn ends engaged therebetween. This arm 106 operates in timed relation with the blades 65, 65^a and 66, of the knotter being designed to move toward the free ends of the lips 95 and 97 25 and after the tying of a knot and the severing the lengths of yarn, to quickly return to a position frictionally gripping the yarn ends against the roughened top face of the plate 93.

30 The knotting and cutting mechanism, in addition to the parts already described, includes coaxing yarn gripping fingers in the form of a pair of flat superposed plates 107 projecting radially from the casing of the 35 knotting device 64 and having between them a third gripping finger which is longitudinally movable across a yarn receiving notch 109 (Fig. 24) in said first plates. These yarn gripping fingers are movable by 40 the spindle 67 through a slot 110 in the cylindrical wall of the knotting device 64 so that they swing immediately over and from one side to the other of the members 65, 65^a and 66.

45 With the above described arrangement of parts, I preferably extend the rod 33 downwardly below the bracket 32 and mount thereon any suitable form of holder or carrier for a plurality of bobbins or spools of 50 yarn, of which there are four in the machine illustrated. From said bobbins, four yarns *w*, *x*, *y*, *z*, lead respectively through suitable 55 openings in the arms of a yarn guiding spider 112 mounted on the post 33, from whence they pass to the eyes of the yarn 60 guiding fingers 49, 50, 51 and 52. From the first of these fingers the yarn *w*, for example, passes upwardly over the rear face of the shield 88 (Fig. 12), thence through an opening in a guide plate 111, between the grid 40 and finger 39, through the eye of the stop-motion yarn sweep 37 and down to the knitting machine proper. There is thus formed between the elements 39-40 65 and the knitting machine cylinder an

elongated loop of yarn which may be shortened or elongated by reason of the ability of the finger 37 to swing vertically.

The ends of the three other yarns *x*, *y*, *z*, 70 pass between the shield 88 and the relatively narrow neck portion 101^a of the guide plate 101, thence between the upper part of the shield 88 and the inner edge of the spring-actuated holding finger 103, through the notch 96 of the angle plate 93 and are 75 gripped between the roughened top surface of the latter and the hooked arm 106 which projects from the spindle 67 of the knotting device.

The several parts of the machine now 80 occupy the relative positions illustrated in Figs. 3 and 4 and also shown diagrammatically in Figs. 12 and 13, so that the knitting machine will knit ribbed fabric from the yarn *w*, which, for example, may be blue 85 as indicated at *w'* in Fig. 33. If it be assumed that the next to the lowest of the elevated links 21^b of the pattern chain 21 is brought, by the intermittent turning of the sprocket wheel 19, into engagement with 90 the roller 27, then the lever 26 is swung on its supporting stud 28 through an angle depending on the height of said link, thus through the rod 29 turning the lever 30 to a corresponding extent. This movement of 95 said lever, through the link 85 swings the controller cam 83 in a counter clockwise direction so that the pawl 81 under the action of its spring is moved in front of the tooth 80 (Fig. 4), as this is drawn to the 100 rear by the action of the eccentric 76 transmitted through the rod 77. At the same time, the above movement of the lever 30 with its selector cam 63 causes the pin 61 to be moved into a position adjacent the 105 lower part of the cam groove 62, with the result that the rod 60 is moved longitudinally toward the left, carrying with it the selector arm 59 and moving the selector 56 into a vertical plane including the yarn 110 guiding finger 50. It will be understood that prior to the above described action and throughout the entire operation of my attachment as subsequently set forth, the knitting machine is in full operation, so that the shaft 12 is continuously turned and with it the eccentric 76 thereon. This eccentric is so set that after the rearward movement of the controller cam 83 above described, said eccentric moves outwardly 115 the bar 77 and with it the tooth 80 so that through the pawl 81 the arm 82 is swung upwardly thus raising the link 86. Such upward movement of said link turns the beveled gear 43 and with it the selector 56 120 in such a direction as to turn the pinion 45 and carrier ring 44 in a counter clockwise direction, at the same time dropping the arm 75.

The turning of the selector depresses the 125

yarn guiding finger 50 into the position indicated in Figs. 14 and 15, in which the yarn end α passing therethrough is drawn down so that the portion thereof leading 5 from said finger lies directly in the path of the angular end of the carrier ring 44, shortly after this begins its movement from the normal position shown in Fig. 12. As before noted, the yarn w which is being fed 10 to the knitting machine, runs from its guide 49 backwardly and upwardly to the lower edge of the shield 88, so that as the yarn α is carried by the ring 44 into the position shown in Figs. 16 and 17, it crosses and 15 engages said yarn w drawing it to the right toward and finally off of point of the right hand end of said shield (Figs. 18 and 19). The tension of the yarn w causes it thereafter to pass in a straight line upwardly 20 between the shield 88 and the guard 101 (Figs. 20 and 21).

In the meantime, the continued rotation of the carrier ring 44 draws the yarn α from its bobbin and lays it in the groove of said 25 ring as the recessed end 44^a thereof swings the end portion of said yarn about its held extremity as a center, until finally the yarn w immediately below the knot catcher plate 111, is also engaged and caused to enter said 30 recess 44^a of the carrier ring. The two runs of yarn w and α are now carried together from the positions indicated in Figs. 20 and 21, back of the lips or tongues 95 and 97 into recesses 96 and 98^a and also into the 35 notch 99^a of the guide 99, being drawn to the left into the angle of and over the blades 65, 65^a and 66 of the knotter, (Figs. 22, 23 and 24).

As the machine continues to operate, the 40 cam 74 carried by the cylinder cam ring comes into engagement with the arm 73, which has been dropped into its horizontal plane of movement by the lowering of the arm 75 by the selector 56 (Fig. 11), so that 45 said arm 73 with the vertical shaft 72 is turned, thereby swinging the arm 71 and through the arm 68, turning the central spindle 67 of the knotting and cutting device 64 in a counter clockwise direction as 50 viewed from above. This causes the yarn gripping fingers 107—108 to move toward the parallel yarns w and α which are so positioned that they enter the notch 109 in 55 said fingers. At the same time the knotting blades 65, 65^a and 66 begin to rotate in a counter clockwise direction (Fig. 25) and in view of their angular form and inclined setting relative to the two lengths of yarn, their extremities move across the latter 60 forming them into a loop around the necks of said blades, by the time they have completed a half revolution. During the continued rotation of said knotting blades, the fingers 107 and 108 with the hooked plate 55 106 continue to swing toward the right and

as the points of said blades swing upwardly from the positions shown in Fig. 27, the holding finger 108 moves radially inward parallel with the finger 107, gripping the two lengths of yarn in the notch 70 109.

It will be understood that the above described rotation of the blades 65, 65^a and 66 stops the feed of the yarn w , but none the less the knitting machine continues to operate, since it takes up the yarn in the long 75 loop between the falling finger 39 and the needle cylinder, the sweep arm 37 gradually swinging down as the loop is decreased in size by reason of the yarn being drawn into 80 the machine.

As the hooked arm 106 swings to the right its forward curved edge slides past the two threads α and w , which being in the recesses 96 and 98, are held by the walls thereof from 85 likewise being drawn out of position toward the right. During the upward turning of the blades 65, 65^a and 66, their ends separate or open so that by the time they have moved into the substantially horizontal position 90 shown in Fig. 28, the double run of the two yarns w and α enters between the blade 65^a and the two blades 65 and 66, being properly positioned for this purpose by the innermost point of the notch or recess 99^a of the 95 element 99. The continued movement of the holding fingers 107 and 108 toward the right causes the loop of yarn around the knotting blades to be drawn from their necks toward their points, which gradually 100 move together until just after the blades 65 and 65^a frictionally grip and hold the yarns, the blades 65^a and 66 finally sever them as shown in Fig. 29. While the severed ends adjacent the loop in the yarn are 105 thus frictionally held, the continued movement to the right of the holding fingers 107 and 108 draws said loop off of said blades, thus forming and pulling tight a knot by the steps indicated in Figs. 28^a, 29^a, 30^a, and 110 31^a. After the completion of the knot, the continued tension exerted by the fingers 107—108 pulls the frictionally held ends from between the blades 65 and 65^a.

In the meantime, the other pair of severed 115 yarn ends as well as the ends y and z are frictionally held between the finger 103 and the adjacent face of the shield 88, while the hooked arm 106 is moved into the position shown in Figs. 30 and 31 beyond the 120 severed yarn ends. By a suitable mechanism whose detail construction forms no part of this invention, the holding fingers 107 and 108 of the knotting device 64 now suddenly release the tied ends of the two yarns and instantly return to their extreme left hand position shown in Fig. 24. With them the holding finger 106 likewise suddenly moves to the left and its hooked end and toothed 125 edge engage the two loose yarn ends which 130

project above the top of plate 92, feeding the short one of said ends toward a chute 130 and carrying the other end across and gripping it against the roughened top surface 5 of the plate 93 where it with the ends y and z are immovably held.

The release by the fingers 107-108 of the tied ends of the yarns w and x permits the sweep arm 37 of the stop motion moving 10 upwardly to its normal position to take up any slack in said yarn and the knitting machine is now fed by the yarn z which is laid by the clockwise movement of the carrier ring 44, between the latter and the back 15 face of the shield 88; the lip 102 preventing said yarn from entering between the guard plate 101 and the shield 88 where it might engage and draw upwardly with one or more of the other yarns.

10 It is to be understood that when the parts 20 occupy the positions indicated in Fig. 28, the carrier ring 44 begins its return movement in a clockwise direction as the link 86 is drawn down by the action of the eccentric 76 transmitted through the rod 77 and the arm 77^a which acts to positively turn the arm 82 with the gear 43 and sleeve 45^a. Such turning of said gear so turns the selector 56 that the previously depressed yarn 25 finger 50 is permitted to move to its upper position under the action of its spring 54.

The turning of the sprocket wheel 19 has now moved the chain 21 sufficiently to cause the roller 27 to pass off of its actuating link 30^b, whereupon the spring 31 turns the lever 30 in a clockwise direction, swinging the controller cam 83 under the pawl 81 so as to prevent further movement of the arm 82, even though the rotation of the eccentric 40 76 reciprocates the rod 77. At the same time the movement of the cam 63 with the lever 30 returns the selector rod 60 toward the right to its extreme position in the plane of the yarn guiding finger 49, where it maintains the arm 75 in the raised position necessary to hold up the vertical shaft 72 with the shoe 73 above the plane of rotation of the cam 74 on the cylinder cam ring.

50 The machine will now knit any required number of courses to form a black stripe x' (Fig. 33) whose width will depend upon the number of low links in the pattern chain 21 before another high link is brought into engagement with the roller 27, as above explained. When this again occurs, the above described cycle of operations is repeated and if it be assumed that the yarn guiding finger 55 52 is depressed, then the yellow yarn z fed through said finger will be knotted to the black yarn x which has been previously fed through the finger 50 and a yellow stripe z' will be knitted (Fig. 33).

For making the fabric illustrated diagrammatically in this latter figure, the pattern chain is so assembled that after the yel-

low stripe z' is knitted, another black stripe x' is formed, followed by a relatively wide band y' of blue yarn. This is accomplished by causing the yarn delivered through the finger 51 being tied to the yarn previously fed through the finger 50. It is thus possible to knit the fabric with different designs of stripes and it is obvious that instead of changing the colors of the yarns, their materials and patterns may be varied in order to produce desired ornamental or useful effects.

It is to be noted that when yarn is being fed from the finger 52 at the extreme left hand end of the series and it is desired to change, tie or connect it to some other yarn, the movement of the end of this latter yarn by the carrier ring 44 naturally cannot engage the yarn z to draw it from behind the shield 88 to a position between the latter and the guard plate 101, as is required in order that the above operations may be carried out as described. I, therefore, mount on the carrier ring 44, for example on its arm 47, a projecting tongue 120 (Figs. 34 30 and 35) which as said ring turns, moves in a circular arc immediately outside of the circularly curved edge of the shield 88, and picks up the yarn z from the finger 52, carrying it over the rear face of the shield 88 to 35 the point thereof, where it is free to move into a position immediately back of the guard plate 101. Thereafter the operations proceed as previously described.

In my machine as so far described, the 40 spring-actuated finger 103 for temporarily holding the inactive yarn ends, is moved against the action of its spring by said yarn ends themselves so that the strength of the spring and consequently the holding 45 ability of said finger is limited. I find, however, that under certain conditions as for example when silk yarn is being operated on, it is necessary to employ a stronger spring than would permit the above method 50 of operation and therefore provide the construction illustrated in Figs. 37 to 41, inclusive, for positively moving said finger in one direction. In this preferred form of my device the hooked arm 106 has the form indicated at 106^a, Fig. 41 and includes a projecting lug 150 designed to cooperate with an arm 151 projecting from the temporary yarn holding finger 103^a. The latter is acted on by a relatively powerful spring 55 105 to confine yarns between its under surface and the roughened top surface of the plate 93, but is swung outwardly and held in an inactive position by the lug 150 as long as the hooked arm 106^a is in position to hold the yarn ends. When, however, said arm is swung to the right as indicated in Figs. 28 et seq., the lug 150 moves away from the arm 151, permitting the finger 103^a 60 to swing in under the action of its spring 110 115 120 125 130

to grip and firmly hold the yarn ends. The return of the hook arm 106^a to its normal position acts through the arm 151 to swing the temporary holding finger 103^a outwardly.

While the carrier ring 44 has been found to operate satisfactorily as above described, I have discovered that the machine may be materially simplified by giving this element 10 the construction illustrated in Figs. 37, 38 and 39. For this purpose, I provide the sleeve 45^a with an arm 47^a which at its outer end has formed integral with it a relatively short arcuate extension 44^c projecting from 15 it in a counter-clockwise direction. This extension is preferably angular in cross section and it has a sharp notched or angular forward edge for picking up and transferring the yarn from any one of the fingers 20 49, etc., in the manner above described in connection with the carrier arm 44. In place of the projecting tongue 120, I may mount on the arm 47^a a projecting pin 120^a 25 so positioned as to perform the function of said tongue in carrying around the point of the shield 88 the thread which leads from the extreme left hand yarn guide 52.

By long continued operation, I have found the mechanism above described to satisfactorily perform the work for which it was 30 designed, the several parts acting with certainty and requiring a minimum of attention. Obviously, the number of yarn sources and the number of yarn feeding fingers, 49, 50, etc., may be made more or less 35 than four without departing from my invention which broadly contemplates the provision of mechanism for automatically connecting one or any number of yarns successively to a yarn or thread while it is 40 being fed to a knitting machine.

In that form of my invention shown in 45 Figs. 37—39, I have given the shield the form indicated at 101^b, extending it upwardly and inwardly so that it will positively guide both threads of a pair being tied and effectually prevent either of them from springing or bending away from the knotter during the 50 tying operation. With this construction, I have found it possible to continuously operate my attachment in connection with the knitting of the most springy forms of 55 artificial silk.

I claim:

1. The combination of a circular knitting machine; a series of yarn sources; mechanism remotely situated relative to the knitting unit of said machine for successively and unrestrictedly selecting different yarns 60 from said sources; and means adjacent said selecting mechanism for knotting the end of each succeeding selected yarn to the yarn being fed to the knitting unit, and severing the running yarn from the newly selected 65 yarn adjacent the said formed knot.

2. The combination of a circular knitting machine including a yarn controlled stop motion; a plurality of different yarn sources; with means, remotely situated relative to the knitting unit of said machine, for automatically and unrestrictedly selecting and knotting yarns from said sources end to end and delivering them through said stop motion mechanism in a continuous length to the knitting unit of said machine. 70

3. The combination of a circular knitting machine; a stop motion therefor including at least one yarn controlled member; a plurality of different yarn sources; with means 75 remotely situated with respect to the knitting unit of said machine for automatically selecting and knotting together end to end yarns from said sources and delivering them successively to and through said yarn controlled member of the stop motion in a continuous length to the knitting machine. 80

4. The combination of a circular knitting machine including a stationary needle cylinder; and a plurality of stationary yarn sources; with means 85 remotely situated relative to said cylinder for automatically and unrestrictedly selecting and knotting yarns from said sources in end to end succession to form a continuous length of yarn and delivering the same to the needle cylinder 90 while the machine is in operation. 95

5. The combination of a circular rib knitting machine including a stationary cylinder; a stationary dial; stationary yarn sources; mechanism remotely situated relative to said stationary cylinder and dial for 100 successively and unrestrictedly selecting yarns from said sources; and a device for automatically knotting to a yarn being fed to the knitting machine, each of the other 105 yarns as it is selected.

6. The combination of a circular knitting machine; a pattern device actuated thereby; a plurality of yarn sources; means remotely 110 situated with respect to the knitting unit of said machine and controlled by said pattern device for successively and unrestrictedly selecting yarns from said sources; with means for automatically knotting the end of the selected yarn to another yarn previously fed to the knitting machine and thereafter cutting off the latter yarn. 115

7. The combination of a circular knitting machine including a rotary cam; a pattern device actuated by said machine; a plurality 120 of yarn sources; mechanism remotely situated with respect to the knitting unit of said machine and controlled by said pattern device for successively and unrestrictedly selecting the yarns from said sources; and a device operated by said cam for knotting each yarn as it is selected end to end, to a 125 yarn previously fed to the knitting machine.

8. The combination of a circular knitting machine; a pattern chain actuated thereby; 130

a plurality of different yarn sources; mechanism remotely situated with respect to the knitting unit of said machine and controlled by said pattern chain for successively and unrestrictedly selecting yarns from said sources; and a device for knotting each yarn as it is selected end to end to a yarn previously fed to the machine.

9. The combination of a circular knitting machine; a pattern chain actuated thereby; a plurality of different yarn sources; mechanism remotely situated with respect to the knitting unit of said knitting machine and controlled by said pattern chain for successively and unrestrictedly selecting yarns from said sources; and a device actuated by the knitting machine for tying the yarns as they are selected, end to end to a yarn being fed to the machine.

10. The combination of a circular knitting machine; a pattern chain actuated thereby; a plurality of different yarn sources; mechanism remotely situated with respect to the knitting unit of said knitting machine and controlled by said pattern chain for successively and unrestrictedly selecting yarns from said sources; and a device controlled by the pattern chain but actuated by the knitting machine, for knotting each yarn as it is selected end to end, to a yarn being fed to said machine.

11. The combination of a circular knitting machine; means for holding a plurality of yarns while another yarn is being fed to the machine; a pattern controlled device remotely situated with respect to the knitting unit of said knitting machine for successively and unrestrictedly selecting said held yarns; a knotting device adjacent said selecting means; and means for delivering to the knotting device any selected yarn, with a yarn being fed to the machine; and means for actuating said knotting device to tie together end to end said two yarns.

12. The combination of a circular knitting machine; a plurality of yarn sources; means remotely situated with respect to the knitting unit of said knitting machine for successively and unrestrictedly selecting the yarns from said sources; a knotting device; means for delivering to said knotting device each yarn as it is selected with a yarn being fed to the machine; means for actuating said device to tie together said two yarns; means for temporarily holding both yarns from moving during the operation of the knotting device; and means for shearing the two adjacent yarns intermediate the formed knot and the holding means.

13. The combination of a circular knitting machine; a plurality of yarn sources; means remotely situated with respect to the knitting unit of said knitting machine for successively and unrestrictedly selecting the yarns from said sources; a knotting device;

means for delivering to said knotting device each yarn as it is selected, with the yarn being fed to the machine; means for actuating said device to tie together end to end said two yarns; means for temporarily holding both yarns from moving during the operation of the knotting device; with a stop motion mechanism including an element for yieldingly supporting a length of yarn between the holding device and the knitting unit of the machine to permit of the delivery of yarn to the latter while said yarn is temporarily held from feeding and for stopping said machine if the thread is removed from said yieldable element, or becomes slack thereon.

14. The combination in a device for connecting yarns of a series of yarn guiding fingers; mechanism for unrestrictedly selecting and actuating any of said fingers; and a knotting device for tying the end of the yarn from a selected finger to the yarn being fed through another one of the fingers, and thereafter cutting off the said running yarn adjacent the formed knot.

15. The combination in a yarn connecting device of a series of yarn guiding fingers; mechanism for unrestrictedly selecting and actuating any of said fingers; means for holding yarns from certain of said fingers while another yarn is being fed through its finger; and means for tying together said latter yarn and the yarn presented by said selector mechanism; said means including a device for cutting off and a device for delivering to the holding means said yarn previously fed.

16. The combination in a device for connecting yarns of a series of yarn guiding fingers; mechanism for unrestrictedly selecting and actuating any of said fingers; means for holding yarn passed through said fingers while another yarn is being fed; a knotting and cutting off device; and a member for presenting to said device the yarn from the finger actuated by the selector mechanism with the yarn which is being fed.

17. The combination in a device for connecting yarns of a series of yarn guiding members; means for unrestrictedly selecting and actuating said members to move them to yarn selective positions; a knotting device; and a rotary member for delivering to the knotting device the yarn selected by one of said members with a yarn from one of the other members.

18. The combination in a device for connecting yarns of a series of yarn guiding members; means for unrestrictedly and selectively actuating said members to move them to yarn selecting positions; a knotting device; a rotary member for presenting to the knotting device the yarn selected by said member with a yarn from one of the other

members; with means for preventing movement of said latter yarn during the operation of the knotting device.

19. The combination in a device for connecting yarns of a series of yarn guiding members; means for unrestrictively selecting and moving any one of said members to a yarn selecting position; a knotting and cutting off device; a mechanism for presenting to said knotting and cutting off device the yarn selected by said member and another yarn from one of the other members; and means for actuating the knotting and cutting off device.

20. The combination in a device for connecting yarns of a series of yarn guiding members; means for unrestrictively selecting and moving any one of said members to a yarn selective position; a knotting and cutting off device; mechanism for presenting to said knotting and cutting off device the yarn selected by said member and another yarn from one of the other members; means for actuating the knotting and cutting off device; and means for holding the cut off yarn ends.

21. The combination in a device for connecting yarns of a series of yarn guiding fingers; means for unrestrictively selecting and moving any one of said fingers to a yarn selective position; means for holding the yarns after their passage through said fingers; a knotting and cutting off device; a rotary member for presenting to said device the yarn from any finger in a selective position, with the yarn from one of the other fingers; means for actuating said knotting and cutting device to tie together said two yarns; and means for temporarily holding said two yarns from moving during the operation of the knotting and cutting off device.

22. The combination of a series of yarn

guiding fingers; a knotting device; mechanism for unrestrictively selecting and moving any one of said fingers to a yarn selective position; means for guiding yarn from one of said fingers to a knitting machine; and a member for presenting to the knotting device the yarn from the latter finger with that from a finger in a selective position.

23. The combination of a series of yarn guiding fingers; a knotting device; mechanism for unrestrictively and selectively moving said fingers to a yarn selective position; means for guiding yarn from one of said fingers to a knitting machine; member for presenting to the knotting device the yarn from the latter finger with that from a finger in a selective position; means for cutting off the former yarn after the operation of the knotting means; and a device for holding the cut off yarn with the yarns from other yarn fingers.

24. The combination in a device for connecting yarns of a series of yarn guiding fingers; means for unrestrictively selecting and moving any of said fingers to a yarn selective position; means for guiding yarn from any one of said fingers to a knitting machine; means for tying together the yarn from a finger in a selective position and the yarn being fed to the knitting machine and thereafter cutting off the latter; means for holding the ends of the inactive yarns; and a member for separating the yarn being fed to the machine from the inactive yarn.

25. The combination of a series of yarn sources; a series of yarn fingers respectively receiving yarn from said sources; a knotter; a yarn transfer member for carrying yarn to the knotter and means for selectively moving the yarn fingers into the path of said transfer member.

WALTER LARKIN.
